UNITED STATES PATENT OFFICE.

ANSON W. ALLEN, OF BIRMINGHAM, ALABAMA.

FURNACE-PORT.

1,076,540.

Specification of Letters Patent. Patented Oct. 21, 1913.

Application filed January 2, 1913. Serial No. 739,666.

To all whom it may concern:

Be it known that I, ANSON W. ALLEN, a citizen of the United States, residing at Birmingham, Alabama, have invented certain new and useful Improvements in Furnace-Ports, of which the following is a specification.

My invention relates to open-hearth furnaces and has particular reference to novel means for cooling the ports of such furnaces.

It has been found in practice that the arch separating the gas and air ports of open-hearth furnaces is affected by the intense heat and disintegrates, particularly at the point or nose thereof. When this has progressed to a certain point the heat must be withdrawn and the arch rebuilt. This is necessary inasmuch as the flames resulting from the combustion of the gas and air at the nose of the arch will, unless the arch is properly formed, impinge against the roof, destroying the same whereas the flames should be directed downwardly against the bath of metal on the hearth.

Numerous means have been suggested for cooling these arches and many thereof include meritorious features. Some objections are present, however, and it is the purpose of the present invention to overcome certain of the objections in a device which shall be simple and easily installed, all without unnecessary expense.

One of the principal objects of the present device is to provide cooling means which shall be inherently self-supporting and which shall notwithstanding be composed of a plurality of units, any one of which may be removed and replaced by one in operative condition all without delaying the operation of the furnace.

A further object is to provide such means which shall not make the operation and length of life of the furnace dependent upon a constant supply of cooling water. In one or more of the devices at present in use, should the supply of water fail, the arch would at once disintegrate and the furnace be necessarily shut down until repairs could be made. In my device should the supply of water fail the cooling means would burn out but the operation of the furnace could be continued successfully for a large number of heats without difficulty. In the meantime other cooling devices might be installed and the proper operation resumed. Such advantage is dependent on the instal-

lation of the device in connection with a refractory self-supporting arch, beneath which the metallic arch is located. This metallic arch is composed of a plurality of trapezoidal metallic boxes placed longitudinally of the furnace with the outer ends projecting through the end wall of the furnace and with the diagonal sides of the boxes in contact. Thus any one of the boxes may be removed and replaced. This requires, however, that the remaining boxes shall be supported when a unit is removed. Therefore I provide a short auxiliary arch of refractory material beneath the metallic arch. This serves the double purpose of supporting the units when one of their number is removed and of preventing the undue cooling of the outgoing burnt gases prior to entering the checkers.

The invention will be more readily understood by reference to the accompanying drawings, wherein—

Figure 1 is a longitudinal section through one end of an open-hearth furnace having my novel water-cooling means applied thereto; Fig. 2 is an end elevation partly in section, of the same; Fig. 3 is an end elevation of one of the cooling units, and Fig. 4 is a longitudinal section through one of the units.

Referring more particularly to the drawings it will be seen that the furnace which may be of the usual construction is provided with a gas port 10 and air ports 11. These ports are separated by an arch 12 of refractory material which arch extends inward of the furnace to the proper or "ideal" point in order to secure proper combustion and direction of the flames. Beneath the refractory arch 12 I provide a metallic water-cooled arch composed of a plurality of units 13. These units are as shown in Fig. 3 in the form of a trapezoid in cross section and are closed at their inner and outer ends by plugs 14—15 respectively which may be welded in place. The plug 15 is apertured to accommodate a fitting 16 to which is connected an overflow pipe 17. A further overflow pipe 17^a 105 is provided delivering into a trough 17^b. Water is supplied to the unit through pipe 18 connected to a header 19 and extending to a point near the inner end of the unit 13. By reference to Fig. 2 it will be seen that 110 by placing a plurality of these units 13 side by side a metallic arch is formed.

Preferably the units forming the marginal edges of the metallic arch are seated in the vertical walls which serve to outline the width of the gas port. Thus they assist in maintaining the opening at the proper size.

- 5 In order to provide means for supporting the units in case one thereof is removed for repair and also for the purpose of preventing the undue cooling of the outgoing 10 gases, I provide a short, auxiliary arch 20 of refractory material. This arch is likewise self-supporting and preferably extends inward under the cooling boxes about half the length thereof in the furnace.
- 15 The advantages of the present construction are many and such advantages might be secured by the use of obvious modifications in the construction. Such modifications as are within the scope of my claims I consider within the spirit of my invention.

I claim:

- 20 1. Cooling means for the ports of open-hearth furnaces, comprising in combination an arch, an underlying longitudinally extending metallic arch, said underlying arch being made up from a plurality of units, each unit comprising a longitudinally extending box, angular in cross section, the sides of the units being in engagement, and 25 means for supplying cooling liquid to each unit, substantially as described.
- 30 2. Cooling means for the ports of open-hearth furnaces, comprising in combination a refractory arch, a plurality of underlying,

longitudinally extending water-cooling units 35 each unit having the form of a trapezoid in cross-section, the diagonal sides of said units being in engagement whereby a metallic arch is formed, and means for supplying liquid to said units, substantially as 40 described.

3. In a furnace, the combination with the gas and air intakes of a division wall formed at the junction of said intakes said wall being composed of upper and lower 45 self-supporting refractory arches and an intermediate water-cooled metallic arch, said metallic arch being composed of a plurality of longitudinally extending boxes with their sides in contact, substantially as described.

4. In a furnace having gas and air ports, a division wall in the form of an arch, said arch being composed of an upper refractory, self-supporting arch, a shorter lower 55 refractory self-supporting arch and an intermediate metallic, normally self-supporting watercooled arch, said arch being made up of a plurality of water-cooling units, whereby any one thereof may be removed 60 and replaced, said lower arch meanwhile supporting the remainder of the units, substantially as described.
